COWTAIL HOLDER

Jacob Kunkle, Wilson, Kans.

Application January 10, 1936, Serial No. 58,483

9 Claims. (Cl. 119—105)

My invention relates generally to cowtail holders and particularly to a device which may encircle the hind leg of the animal and to which the tail may be secured to prevent its movement during the milking or other work in the vicinity of the animal.

The objects of the invention are, first; to provide a cowtail holder simple in construction and easy to operate, providing a positive acting and rugged inexpensive device.

Second; to provide a cowtail holder in which the leg clamping means are locked in clamping position prior to the tail clamping operation.

Third; to provide a cowtail holder capable of being adjusted in size to snugly fit the leg of the animal upon which used.

Further objects and advantages of the invention as well as its operation will be apparent by referring to the following description in connection with the accompanying drawing in which:

Fig. 1 is a perspective view of the device in full clamping position.

Fig. 2 is a similar view with the tail clamping means in disengaged position.

Fig. 3 is a similar view with both the tail and clamping means in fully disengaged position, the device being slightly modified, means being provided for adjusting the device to fit the particular size of leg on which applied.

Fig. 4 is a top plan view of the device in full clamping position.

Fig. 5 is a front end view of the same, and

Fig. 6 is a fragmentary, vertical, sectional view on the line 6—6 of Fig. 5 showing the tail clamping means in clamping position.

Referring now to the drawing by numerals of reference, 1 and 2 designate leg clamping members, member 2 being pivotally secured to member 1 at 3, the other end of member 1 being secured to transverse portion 4 having slot or opening 5 adapted to be engaged by bifurcated end 6 of actuating or locking member 7 having fingers 8 and 9 adapted to engage slot 5 and end 10 in transverse portion 4 and clamping member 2.

The clamping member 2 is shown as being formed of a wire or rod providing opening 2'', but it may be made of a solid piece of material with a suitable slot at locking end 10.

A resilient member or spring 11 is mounted between the end 12 of transverse portion 4 and actuating or locking member 7. The spring 11 in combination with the transverse member 4 forms a tail clamping means as shown in Figs. 1, 5, and 6.

In operating the device, the leg clamping mem-

bers 1 and 2 are placed around the leg L of the animal and member 2 is moved toward member 1 until end 10 is adjacent the slotted end of transverse member 4. (See Fig. 2.) Actuating or locking member 7 is swung toward transverse member 4 until fingers 8 and 9 of bifurcated end 6 engage slot 5 and end 10 of clamping member 2. The tail 13 may be inserted at this time between transverse member 4 and spring or retaining member 11, and the spring actuating and clamp locking lever 7 may be swung in the direction shown by arrow in Fig. 2, until abutting clamping member 2, at which time spring 11 will have passed beyond a vertical plane passing through transverse extension 4, to effectively clamp tail 13 between said spring 11 and member 4. (See Figs. 5 and 6.) In full clamping position, finger 9 is engaging slot 5 and finger 8 is abutting end 10 of clamping member 2, the action of spring 11 retaining locking member in locking position.

The device may be modified as shown in Fig. 3 to permit adjustment of locking or clamping members 1a and 2a to fit the leg of the animal upon which the device is to be used. Clamping member 1a has extensible portion 1', slidably supported thereon by means of threaded extension 14 passing through slot 15, a suitable nut 16 being provided for locking members 1a and 1' in adjusted position. Clamping member 2a has extension 2' having looped ends 17 slidably positioned on member 2a, the ends 18 of which are also looped about extension 2' to provide means for adjusting clamping member 2a.

From the foregoing it will be apparent that I have provided a novel tail holder which may be quickly and effectively applied and will provide positive tail clamping means, inexpensive and sturdy in construction.

As herein described and drawn, the invention illustrates the preferred embodiments of same as it now appears to me, but I reserve the right to make such changes in form, proportion and details of construction as do not depart from the spirit of the invention.

What I claim as new and desire to secure by Letters Patent is:—

1. A tail holder comprising a pair of leg-clamping members, a transverse portion on one of said members, and means for securing the other clamping member to the transverse portion, said means including means for clamping the tail of the animal to the transverse portion.

2. The structure as specified in claim 1, said first named means comprising a clamping lever

engageable with the transverse portion and the second clamping member.

3. The structure as specified in claim 1, each of said leg clamping members comprising slidably related portions, and means for locking said sliding portions of the leg clamping members in adjusted position substantially as described and for the purpose specified.

4. A cowtail holder comprising a pair of leg clamping members, one of said clamping members carrying a transverse member at one end thereof, the other end of said last mentioned clamping member being pivotally secured to one end of the second clamping member, and means for removably securing the other end of the second clamping member to one end of the transverse member, said means including a member for securing the animal's tail to the transverse member.

5. A cowtail holder comprising a pair of leg clamping members, one of said clamping members carrying a transverse member at one end thereof, the other end of said last mentioned clamping member being pivotally secured to one end of the second clamping member, a clamping lever for removably securing the other end of the second clamping member to one end of the transverse member, and spring means between the transverse member and the clamping lever for maintaining said clamping lever in clamping position and for securing the animal's tail to the transverse member.

6. A cowtail holder comprising a pair of leg clamping members, one of said clamping members carrying a transverse member at one end thereof, the other end of said last mentioned clamping member being pivotally secured to one end of the second clamping member, a clamping lever and spring means for removably secur-

ing the other end of the second clamping member to one end of the transverse member, said spring means being connected with said transverse member and movable into and out of tail holding relation therewith.

7. A tail holder comprising a pair of leg clamping members, a transverse portion on one of said members, and means for securing the other clamping member to the transverse portion, said means comprising a clamping lever and spring means engageable with the transverse portion and the second clamping member, said spring means being adapted to retain the clamping lever in clamping position and to clamp the tail of the animal to the transverse portion.

8. A tail holder comprising a pair of leg-clamping members, a transverse portion on one of said members, and means for securing the other clamping member to the transverse portion, said means including means for clamping the tail of the animal to the transverse portion, said first named means including a clamping lever engageable with the transverse portion and the second clamping member, said tail clamping means also comprising means for retaining the clamping lever in clamping position.

9. A tail holder comprising a pair of leg-clamping members, a transverse portion on one of said members, and means for securing the other clamping member to the transverse portion, said means including means for clamping the tail of the animal to the transverse portion, said first named means comprising a clamping lever engageable with the transverse portion and the second clamping member, said tail clamping means including a resilient member between the transverse portion and the clamping lever.

JACOB KUNKLE.
